UNITED STATES PATENT OFFICE.

JAMES ARTHUR TERRY, OF POCOHONTAS, IOWA.

PORTABLE CABINET-LAVATORY.

1,374,778.

Specification of Letters Patent. Patented Apr. 12, 1921.

Application filed March 20, 1920. Serial No. 367,424.

To all whom it may concern:

Be it known that I, JAMES A. TERRY, being a citizen of the United States of America, and resident of Pocahontas, Pocahontas 5 county, Iowa, have invented a new and useful Portable Cabinet-Lavatory, of which the following is a specification.

The object of this invention is to provide a lavatory and toilet device of cabinet form 10 adapted to be carried in a suitable manner in or on a vehicle, as for instance on the running board of an automobile.

A further object of this invention is to provide a cabinet adapted to contain a supply 15 of water and of toilet accessories and also being equipped with a wash basin adapted to be contained within the cabinet and moved to convenient position for use at times.

20 My invention consists in the construction, arrangement and combination of elements hereinafter set forth, pointed out in my claims and illustrated by the accompanying drawing, in which—

25 Figure 1 is a side elevation showing my improved cabinet lavatory mounted on the running board of a vehicle, the door of the cabinet being in open position. Fig. 2 is a plan of the same, a portion of the cabinet 30 being shown in section. Fig. 3 is a cross section on an enlarged scale, the door being in closed position. Fig. 4 is an end elevation and Fig. 5 a side elevation, partly in section, illustrating means for mounting a 35 roller.

In the construction of the device as shown the numeral 10 designates generally a housing, which may be made of sheet metal and of any suitable size. At each end the housing 40 10 is provided with a base flange 11 extending outwardly in a horizontal plane and said flanges are adapted to be secured as by bolts 12 to a suitable support 13, such as the running board of a motor vehicle. The 45 outer side of the housing 10 is formed with a relatively large opening 14, preferably comprising the greater part of that side of the housing farthest from the body of the vehicle when the device is mounted as above suggested. The opening 14 is closable by a door 15 pivotally secured at one side margin by hinges 16 to the housing. A gasket or cushioning pad 17 is mounted on the inner face of the door 15 and extends around 50 the margin thereof and said gasket is adapted to contact marginal portions of the

opening 14 when the door is in closed position, in order to form a tight closure and also to prevent rattling. A water tank 18 is rigidly mounted in the upper rear portion 60 of the housing 10, that is to say on that side of the housing nearest to the vehicle body, and said tank preferably extends longitudinally about one-half the transverse dimension thereof. The water tank 18 may be 65 filled through a nozzle 19 extending through the top of the housing and closable by a cap 20. A drain cock 21 is mounted in the lower portion of the water tank 18, preferably on the side nearest the opening 14, by means 70 of which water may be withdrawn from the tank.

A shelf 22 is fixed to and carried by the inner lower portion of the door 15 and when said door is in closed position said shelf occupies a position within the housing 10 parallel with and just above the bottom of said housing. The shelf 22 may be of substantially segmental form in plan, thus providing a maximum area of the shelf and yet 80 permitting it to enter the housing as the door is swung through an arc to closed position. A wash basin 23 is carried by and occupies the major portion of the area of the shelf 22, and when the door is moved toward its 85 closed position, said shelf carries the basin 23 beneath the cock 21 of the water tank to facilitate supplying said basin with water. The basin 23 is formed with a drain opening in its bottom normally closed by a stopper 90 24.

A towel roller 25 is mounted longitudinally of the upper portion of the housing 10, in the space between the tank 18 and the front of the housing and said roller is adapted to carry a supply of tissue toweling such as 26 in roll form. A rack or pocket 27 is mounted in one corner portion of the housing 10, beneath the tank 18, and is adapted to contain towels such as 28, wash rags or 100 other toilet accessories.

A number of spring clips 29 are secured to the inner surface of the door 15, above the plane of the basin 23, and said clips are adapted to support toilet articles such as a 105 comb 30, a brush or broom 31 and the like. One of the clips also may be employed to support a funnel 32 which may be used in the operation of filling the tank. A portion 33 of the shelf 22 also may be arranged as 110 a container for soap such as 34.

This device provides a very convenient

accessory for cross-country travelers and tourists, furnishing as it does a convenient means for carrying a supply of clean water for washing purposes, together with towels, 5 soap and other toilet articles. When traveling the door is kept in closed position as by means of a latch device 35 and the toilet articles and wash basin are thus protected from dust and dirt. When it is desired to use the 10 lavatory device the door is unlatched and opened slightly to permit the entrance of a person's arm to open the water cock 21 and permit water to flow from the tank 18 to the wash basin 23. When this is done the 15 door is opened farther so that the basin 23 is easily accessible for washing purposes, after which the basin may be emptied by removing the stopper 24 and allowing the water to flow to the ground. When the 20 door is opened the towels and other toilet articles are within easy reach.

The towel roller 25 preferably is carried by apertured ears or clips 36 mounted on inner surfaces of the end walls of the housing 10, said ears or clips being offset inwardly from the walls between their ends and having their apertures 37 engaged by studs 38 in the ends of the roller, as shown in Figs. 4 and 5.

30 I claim as my invention—

1. A device of the class described, comprising a portable housing formed with a relatively large opening in one side wall, a door hinged on a vertical axis at one side 35 margin to said housing and adapted to close said opening, a water tank being formed in

the upper portion of said housing, said water tank being formed with a drain cock on its lower side, a horizontal shelf fixed to the inner side of said door, and a lavatory 40 basin carried by said shelf and adapted to be moved to a position beneath said drain cock and to be inclosed within the housing when the door is shut and being supported in a position for use outside of said housing when the door is in open position, said basin remaining in horizontal position irrespective of the position of the door relative to the housing.

2. A device of the class described, comprising a housing formed with a relatively large opening in one side wall, a door hinged on a vertical axis at one margin to said housing and adapted to close said opening, a water tank being formed in the upper portion of said housing, said water tank being provided with a drain cock on its lower side, a horizontal shelf fixed to the lower portion of the inner side of said door, a lavatory 55 basin carried by said shelf and adapted to be moved to a position within the housing and beneath the drain cock of said tank when the door is in closed position and adapted to be moved to a position for use outside of said housing when the door is in 60 open position, said basin being formed with a drain opening in its bottom, and a stopper normally closing said drain opening.

Signed at Pocahontas, in the county of Pocahontas and State of Iowa, this 11th day 70 of March, 1920.

JAMES ARTHUR TERRY.
